TEA BAG STRAINER

William F. Taylor, Philadelphia, Pa.

Application December 4, 1952, Serial No. 22,543

Term of patent 14 years

(Cl. D44—29)

To all whom it may concern:

Be it known that I, William F. Taylor, a citizen of the United States, residing in Philadelphia, in the county of Philadelphia and State of Pennsylvania, have invented a new, original, and ornamental Design for a Tea Bag Strainer, of which the following is a specification, reference being had to the accompanying drawing, constituting a part hereof.

Figure 1 is a front view of a tea bag strainer, the opposite side of which is identical, showing my new design;

Fig. 2 is an end view thereof;

Fig. 3 is a perspective view thereof;

Fig. 4 is a sectional view thereof taken along the line 4—4 of Fig. 2.

I claim:

The ornamental design for a tea bag strainer, substantially as shown and described.

WILLIAM F. TAYLOR.
